UNITED STATES PATENT OFFICE.

HARRY S. READ, OF ITHACA, NEW YORK, ASSIGNOR TO WESTERN ELECTRIC COMPANY, INCORPORATED, OF NEW YORK, N. Y., A CORPORATION OF NEW YORK.

RADIO RECEIVING SYSTEM.

Application filed September 14, 1920. Serial No. 410,235.

To all whom it may concern:

Be it known that I, HARRY S. READ, a citizen of the United States, residing at Ithaca, in the county of Tompkins, State of 5 New York, have invented certain new and useful Improvements in Radio Receiving Systems, of which the following is a full, clear, concise, and exact description.

This invention relates to a circuit arrangement for interlinking three or more circuits in such a manner as to provide a particular functional relationship therebetween, and its principal object is to prevent mutual feeding of power or exchange of energy between 10 two of the circuits but to permit the two circuits to feed independent of each other into the other circuits.

The invention has for its object the provision of means to maintain a relationship 20 of associated circuits such that two of the circuits are independently related to a third circuit or other circuits into which they feed but between which two circuits no interaction can exist.

25 It is a further object of the invention to provide a connection of amplifier or antenna, a local oscillation generator, and a detector, in a heterodyne receiving system which will permit the first and second circuits to feed into a detector circuit but which will prevent the two circuits from feeding into each other.

Further objects of the invention will appear as the specific details thereof are disclosed in the description that follows.

35 As illustrating an application of the invention, which will be hereinafter described in greater detail, the circuit arrangement may be used to interconnect the three circuits of a heterodyne receiving system in 40 which a high frequency wave is received by an antenna circuit and combined with a locally generated wave of slightly different frequency, in a common detecting circuit. It is desired to prevent interference, due to 45 the radiation of the locally generated wave from the receiving antenna. The means of the present invention effectively prevents interference with other stations as well as the waste of energy attendant on the diversion 50 of the energy derived from said local source from its proper channel. The inter-position of any means between the antenna and the circuits of the invention which has unilateral conductivity will, to some extent at 55 least, avoid these undesirable effects. An

amplifier inserted between the antenna and detector circuits might be effective for this purpose but on account of the effective capacity in the tube circuits, the amplifier is not a unilateral transmission circuit and at high 60 frequencies an undesirable amount of energy can pass backwards through an amplifier into an antenna circuit.

In the embodiment of the invention disclosed, the amplifier will be used in this relation in order to conform with practice in this regard, which practice requires amplification of the feeble impulses generated in the receiving antenna. Although a single 65 amplifier has been shown, it may be desirable 70 in many cases to use multistage amplification, which may be accomplished by adding additional amplifiers in series or cascade relation according to well known principles.

In addition to the function of the circuits 75 of the invention, as stated above, to prevent radiation of the locally generated wave, the additional function is accomplished of preventing undesirable modulation. If a voltage derived from the local source is impressed on the output circuit of the amplifier, or amplifiers, it may cause some energy to feed back through one or more of the amplifier units. Whether or not there is an 80 actual feed back, there will be a modulation 85 of two frequencies which are present. This will result in the presence in the input of the detecting device of a complex wave containing components made up of the sum of frequencies concerned and other frequencies, 90 differing from the input components which it is desired to detect and which may under certain circumstances be undesirable. A means such as that of the invention effectively prevents intermodulation before detection of the received, and local frequencies. 95

The invention in one aspect resides in the use of a closed impedance circuit of a conventional four-arm Wheatstone bridge, to junction points of which three circuits are 100 connected, the output (in the particular application chosen, a detector circuit) being connected across one arm or a portion of an arm, and the other two circuits being connected respectively to alternative pairs of 105 opposite junction points. If the bridge is balanced in the usual manner, there is a zero difference of potential between the points at which each of the input circuits are connected, when a difference of potential is 110

impressed upon the bridge by the other input circuit. By proper balancing, the two circuits may accordingly be effectually prevented from feeding into each other. Since the output circuit is associated with only a single arm of the bridge there is always a difference of potential between its terminals when a potential is impressed on the bridge from either input circuit. For the purpose of the detailed description and claims following, a Wheatstone bridge may be defined broadly as a closed impedance circuit in which the impedance elements are of such relative values and so arranged that there are two pairs of points, between the points of each of which there is a zero difference in potential when a difference in potential is impressed between the points of the other pair. It is immaterial, for the purposes of definition, whether the differences of potential are impressed inductively or conductively and, accordingly, the definition includes within its terms various types of balances networks or hybrid coil circuits.

As further illustrating the invention, reference is made to the following detailed description, with its accompanying drawings, in which Fig. 1 is an enlarged view of the circuit arrangements of the invention without reference to the particular types of circuits with which it is adapted to be used and Fig. 2 is a circuit diagram of a preferred system in which the invention may be used.

Referring to Fig. 1, the closed circuit which includes the four impedances Z_1 , Z_2 , Z_3 and Z_4 , is suggestive of the closed impedance circuit of a simple type of Wheatstone bridge in which the impedances here replace the resistances usually shown in the type of Wheatstone bridge used for comparative measurements of resistance. The four arms of the bridge are here shown as impedances to indicate that pure resistances, inductances or capacities, or combinations of the above may be used, provided only that the fundamental condition is observed, which is common to all types of four arm bridges, whether constituted of resistances, inductances or capacities, that is $Z_1/Z_2 = Z_3/Z_4$.

If a difference of potential is impressed across Z_1 , Z_3 for example, by means of circuit C, there will be zero difference of potential between the junction points Z_1 , Z_3 and Z_2 , Z_4 , between which points circuit A is connected. The practical significance of this is that when a potential is impressed on the bridge from circuit C, energy from this circuit cannot feed into circuit A. Conversely when a potential is impressed on the bridge from circuit A, the energy from this circuit cannot flow in circuit C. Since circuit B is associated with a single arm of the bridge and since current flows in this arm, when a difference of potential of either

polarity is impressed on the bridge by either of circuits A and C, there will necessarily be a difference of potential between the points across which this circuit is connected. Accordingly either circuit C or circuit A, 70 each independently of the other, may feed into circuit B, or both circuits may feed simultaneously into circuit B, superposing their separate effects in this circuit.

In applications of the inventive idea hereinafter to be disclosed in specific circuit systems, the circuit B will be designated as the output circuit and the circuits A and C as input circuits. It is immaterial as to the polarity of the respective input terminals, 75 the only essential conditions being the proper balancing of the bridge and the connection of input circuits thereto, each to a separate pair of opposite junction points. It has been suggested in the above that it is 80 immaterial whether the elements composing the bridge are resistances, inductances, capacities or combinations of the three, as far as regards operativeness of the bridge for the purpose described, or how much the impedances of the several arms may differ from each other, as long as the fundamental equation is satisfied. It will now be shown, however, that considerations of efficiency 85 urge a particular choice of elements and amount of the impedance of each. For example, assume that circuit C is connected with or receives its energy from a distant source of power, while circuit A is a part of a local circuit, energy from each being transmitted 90 through the bridge to common circuit B. The energy from the source received at the bridge through circuit C, will be largely decreased on account of absorption of energy 95 between said source and bridge. It is desirable in this case, in which the difference of potential impressed on the bridge by circuit C is small, to transmit the energy through the bridge with as small a loss as possible. This may be accomplished by 100 making Z_3 and Z_4 great as compared with Z_1 and Z_2 respectively. This means that the output circuit is fed from the arm across which the greatest drop of potential occurs. In this case the current through Z_4 when a 105 potential is impressed on the bridge by circuit A, is less than with any other arrangement of impedances, and hence the energy from circuit A is transmitted less efficiently into the output circuit. In other words, increase in efficiency of transmission from circuit C is obtained at the expense of efficient transmission from circuit A. This is permissible since we are greatly concerned with efficiency from circuit C to output, but, since 110 A is a powerful local source, not so concerned with efficiency from circuit A to output.

It should be pointed out here that the impedance of circuit B is a part of the im- 115

pedance of the fourth arm of the bridge and is included in the value of impedances Z_4 in the equation indicating the condition of balance of the bridge. The impedance of the parallel circuits comprising this arm will substantially determine the impedance to be chosen for the other arms in accordance with the preceding analysis. In order that energy from circuit C may feed efficiently into circuit B and with a minimum of loss in the bridge, the bridge portion of impedance Z_4 should be much larger than impedance of circuit B. The impedance of circuit B would ordinarily be of the order of magnitude of at least 600 ohms, and with this value it has been found to be desirable and convenient to make the bridge portion of impedance Z_4 about 6000 ohms. Z_3 would accordingly have a value between these quantities, assuming for convenience that $Z_1 = Z_2$ and $Z_3 = Z_4$. With these comparatively great impedance values, especially in the case where these quantities are made variable in order to balance the bridge, it is preferable to make the larger impedance elements of the bridge pure resistances. Impedances Z_1 and Z_2 are relatively small and fixed in value and may well be condensers since with the high frequencies used in this bridge comparatively small capacity is required. The quality of small fixed condensers, by reason of which their impedance constants vary only slightly with change in frequency and with use as compared with inductances and resistances, commends them for use in the present arrangement.

Referring now to Fig. 2 there is here disclosed the use of a circuit arrangement of the invention, in what may be termed the preferred embodiment, although other uses are contemplated, and the invention should not therefore be construed as in any sense restricted to this embodiment.

There is disclosed a heterodyne receiving system, the system, except as varied by the use of this invention, being old in the art. In this system high frequency waves from the antenna D are amplified by vacuum tube E in the conventional manner, the filaments and plate of which are connected into the circuit C of the bridge arrangement F, the circuits of which are shown the same as in Fig. 1. The circuit C may be connected directly to the antenna without the interposition of the amplifier circuit if the received energy is sufficient to actuate the detector.

Input circuit A is connected with the heterodyne oscillator G through coupled circuits J. The oscillator functions as a generator of high frequency oscillations, the frequency of which is determined by the adjustment of the inductance and capacity of its tuned circuit. In the system shown the oscillator is adjusted to oscillate with a frequency slightly different from the fre-

quency of received signal waves. These two sets of waves of different frequencies are impressed simultaneously upon the detector H to give a "beat" frequency current in the telephone receiving circuit 1. In the system shown, the bridge circuit arrangement functions as described with reference to Fig. 1, to prevent interference between the amplifier and oscillator circuits but to permit each to feed independently into the detector circuit. In Fig. 2 the impedances of the bridge are shown as made up of two condensers and two resistances, for the reason that has been pointed out, although the system would be operative and the theory of operation would apply equally well if the impedances were chosen otherwise, as has also been pointed out.

Although the system disclosed in Fig. 2 has been described as a heterodyne receiving system, the oscillator G may well be made to generate frequencies identical with the amplifier frequency. The system used in this way has practical application in radio telephony as may be seen by a reading of British Patent 102,503. The system disclosed in the present application is capable of use in the manner described in this patent and such use is to be understood as comprised within the scope of this invention.

Although in the example given, an alternating E. M. F. of high frequency is impressed on the bridge arrangement the invention should not be understood to be so limited, the theory of operation not being inconsistent with the use of any type of current whatever in the input circuit. Although the circuit B has been disclosed as connected across one arm of the bridge, it may be connected between any two points between which there is a difference of potential as, for example, across a portion of one arm or across unequal fractions of any two of the impedances in series, although the latter arrangement would obviously be inefficient. The invention should not be considered as limited to the use of a single output circuit, since as many output circuits may be used simultaneously, as there are points between which difference of potential exists. Still further, the circuit B may be inductively instead of conductively coupled with the bridge.

What is claimed is:

1. A circuit system comprising in combination, an input circuit, a second input circuit, an output circuit, and a circuit coupling said input circuits to said output circuit to enable them to impress electromotive forces thereon, said coupling circuit being so arranged with respect to the two input circuits that said input circuits are free from effective coupling whereby neither input circuit is affected by the other.
2. A circuit system comprising an input

circuit, a second input circuit, an output circuit, and a mesh circuit coupling said input and output circuits, the input circuits being connected at conjugate pairs of points in said mesh and the output circuit being connected at a pair of points in said mesh which are non-conjugate with respect to either of said other pairs of points.

3. In a circuit arrangement for radio receiving systems, a receiver circuit, a local oscillation circuit, a detector circuit and a mesh circuit coupling said circuits, the receiver and oscillation circuits being connected to conjugate pairs of points in said mesh, and the detector circuit being connected at a pair of points in said mesh which is non-conjugate with respect to either of said other pairs of points.

4. In combination, a closed impedance circuit, an input circuit, means for impressing a difference of potential from said input circuit between two points in said impedance circuit, a second input circuit, means for impressing a difference of potential from said second input circuit between two points of said impedance circuit which are balanced with respect to the other two points, an output circuit, and means for impressing on said output circuit a potential derived from a third pair of points in said impedance circuit at least one point of which is different from the points in the other two pairs.

5. An anti-feed-back circuit comprising in combination, two impedance branches connected in parallel each branch consisting of two impedance elements, the ratio of the two impedances in one branch being made equal to the ratio of the similarly positioned impedances in the other branch, a circuit connected between the terminals of the impedance branches a second circuit connected between the junction points of the impedance elements in the respective branches, and a third circuit connected between the terminals of any one of the impedance elements.

6. An anti-feed-back circuit as disclosed in claim 5 in which two of the impedances, consisting of the impedance across which the third circuit is connected and the corresponding impedance in the other parallel branch, are relatively large as compared with the other two impedances.

55 7. The anti-feed-back circuit arrangement as disclosed in claim 6 in which the relatively large impedances are non-inductive resistances and the other impedances are condensers.

60 8. An anti-feed-back circuit as disclosed in claim 7 in which the first-mentioned cir-

cuit is connected with the receiving circuit of a radio receiving system, the second-mentioned circuit is connected with a local source of high frequency oscillations, and the third circuit is connected with a detector circuit.

9. A receiving system comprising in combination, a receiving conductor, an assymmetrically conducting means in energy transfer relation thereto, a detector circuit, a local source of high frequency oscillations and an anti-feed-back circuit associated with the above mentioned elements, said anti-feed circuit comprising two impedance branches connected in parallel, each branch consisting of two impedance elements, the ratio of the two impedances in one branch being made equal to the ratio of the similarly positioned impedances in the other branch, the assymmetrically conducting device being connected between the terminals of the impedance branches, the local source being connected between the junction points of the impedance elements in the respective branches and the detector circuit being connected between the terminals of any one of impedance elements.

10. A receiving system comprising in combination, a receiving conductor, a thermionic conducting means associated therewith, a detector circuit, a local source of high frequency oscillations and an anti-feed-back circuit associated with the above mentioned elements, said anti-feed-back circuit comprising two impedance branches connected in parallel, each branch consisting of two impedance elements, the ratio of the two impedances in one branch being made equal to the ratio of the similarly positioned impedances in the other branch, the thermionic conducting device being connected between the terminals of the impedance branches, the local source being connected between the junction points of the impedance elements in the respective branches and the detector circuit being connected between the terminals of any one of the impedance elements.

11. A circuit system comprising in combination, an input circuit, a second input circuit, an output circuit, and a Wheatstone bridge circuit coupling the input circuits whereby interchange of energy in either direction between said circuits is prevented, said output circuit being connected to the bridge at points unbalanced with respect to each of said input circuits.

In witness whereof, I hereunto subscribe my name this 10 day of September, A. D., 1920.

HARRY S. READ.
